UNITED STATES PATENT OFFICE.

CHARLES J. GADD, OF LEBANON, PENNSYLVANIA; ANNA EYRE GADD EXECUTRIX OF
SAID CHARLES J. GADD, DECEASED.

CLIP.

1,304,554.

Specification of Letters Patent. Patented May 27, 1919.

Application filed March 21, 1916. Serial No. 85,533.

To all whom it may concern:

Be it known that I, CHARLES J. GADD, a citizen of the United States, and resident of Lebanon, in the county of Lebanon and State of Pennsylvania, have invented certain new and useful Improvements in Clips, of which the following is a specification.

My invention relates to improvements in means for removably securing two or more objects together and more particularly to an improved quick-acting means for removably securing together a case and its cover, a screw conveyer case and cover for instance, that has to be more or less frequently taken down for the purpose of inspection or repairs.

Screw conveyers are made as long as 250 feet in one run and if the cover and the case be secured one to the other by screws or by bolts and nuts placed generally about four inches apart, which is the usual construction, it will be seen that much time is lost in removing and replacing the hundreds of these articles used whenever it is necessary to remove the cover to get at any trouble within the case. With either the screw or the bolt and nut methods of securing the cover and case, especially where the conveyer is used for feeding pulverized coal, or other finely ground substance, it takes so much time to remove and replace the cover that not infrequently an entire plant has to be shut down for considerable periods to permit this.

My improved fastening for securing the cover to the case, or for detachably securing together other things, consists of a two part clip one part being U shaped and adapted to be slipped over the parts to be secured together, and the other part consisting of a lever carried in bearings in the first part which upon being moved forward will unlock and upon being moved backward will lock the case and cover or other parts that it may hold.

My invention is illustrated in the accompanying drawings forming part of this specification, in which similar numerals of reference indicate similar parts throughout the several views, and in which—

Figure 1, is a perspective view of my improved fastening or clip:

Fig. 2, a top view of the clip when closed:

Fig. 3, a side elevation of Fig. 2:

Fig. 4, an end elevation of Fig. 3: 55

Fig. 5, an end elevation of a screw conveyer case and its cover.

10 is the U shaped part of my clip. Preferably this is constructed from a length of wire sufficiently stout for the strains to 60 which it will be subjected. At its middle this piece of wire is bent to form a bight 11 and is again bent at 12—12' so that its parts 13—13' will be substantially parallel to its parts 14—14'. At its ends it is bent to form 65 eyes 15—15'. The lever 16 is likewise preferably formed of stout wire and at its middle is bent to form a bight 17, the wire extending from this bight forward and being, near its forward end, bent downward to 70 form a cam 18, then upward, at 19, and then outward to form trunnions 20 which are carried in the eyes 15—15' in the stationary part of the clip.

From Fig. 3, in which part of a conveyer 75 case and cover are shown in broken lines, it will be observed that when the lever 16 is moved down so as to cause the cam 18 to close the lid 21 against the top of the case 22 that the cam 18 is off center with the fulcrum 80 or trunnion 20 of the lever 16 hence any upward pressure on the cover 21 will tighten 85 the grip of the cam without tending to lift lever 16.

While on account of cheapness and resiliency I prefer to construct the members of the clip of wire suitably bent, I do not desire to confine myself to the use of this material as it will be evident that other materials, malleable or steel castings, for instance, may be used.

Viewed with respect to the planes of the work to be clamped, my construction, as illustrated, embodies two pairs of parallel arms, the front pair united at the open end 95 and the rear pair terminating in eyes within which the lever-operated cam is pinioned so that the cam projects into the space between for the clamping function and automatically locks by reason of the "off-center" 100

position of the heavier part of the cam when "set."

The front parallel arms form one jaw or member and the back parallel arms the second jaw or member of a resilient clamp, in which each of the four arms is independently resilient and which, viewed in a plane parallel to the paper in Fig. 3, might be regarded as comprising two U-shaped side members, each including the article clamped.

Thus the front and back clamping members have not only the curved connecting wire between to give them resilience, but have the advantage of the spring of a considerable part, at least, of the length of each of the wires from the open end of the clamp to these curved connecting parts.

Having thus described my invention I claim as new and desire to secure by Letters 29 Patent:—

1. A clamp comprising a back member and spaced front members separately resilient throughout the greater part of their lengths in a direction transverse to the back member and providing a space between the back and front members for the article clamped, in combination with a cam pivoted in the front members to project within said space and an operating lever for said cam.
2. A clip for the purposes set forth comprising, in combination, a member formed from a single piece of metal reversely turned at its middle to form a two part arm and reversely turned again to form two arms which will be substantially parallel to one another and to the two parts of the first arm and having the ends of the two arms, terminating in coaxial eyes, and a second member reversely turned at its middle to form a lever, then extending downwardly and upwardly to form a cam and then outwardly to form trunnions adapted to be carried by and to turn in the eyes

Copies of this patent may be obtained for five cents each, by addressing the "Commissioner of Patents, Washington, D. C."

found in the ends of the metal forming the first member.

3. A U-shaped clamp comprising parallel pairs of parallel arms, one pair being united at the open end of the clamp and the other pair terminating in co-axial eyes turned away from the clamp, in combination with a wire lever having terminal trunnions fitting in the eyes and an intermediate cam extending downwardly from the trunnions toward the open end of the clamp to lie off-center when the lever is closed, and then toward the closed end of the clamp and there united to form the lever handle.

4. A U-shaped clamp comprising parallel arms united at the end to form one jaw and each united to parallel arms forming a second jaw, the second pair of arms terminating in co-axial eyes, in combination with a lever having parallel arms united to form a handle and at its opposite end extending laterally in the form of trunnions to fit in the eyes and having a cam between the handle and trunnions.

5. A clamp upon one end comprising parallel spaced pairs of parallel arms, the ends of arms from opposite pairs being connected to close one end of the clamp and the opposite ends of the arms of one pair being united, the free ends of the other pair terminating in co-axial eyes, in combination with parallel connected arms forming a lever terminating at their free ends in oppositely directed trunnions fitting the eyes and both bent toward the opening in the clamp between the lever and trunnions to form cams which are off-center in the closed position of the clamp.
